United States Patent Office

Des. 188,382
Patented July 12, 1960

188,382

GUN HOLSTER

Frank A. Stella, Lyndhurst, N.J., assignor to The Hubley Manufacturing Company, Lancaster, Pa., a corporation of Pennsylvania

Filed Oct. 23, 1959, Ser. No. 58,047

Term of patent 14 years

(Cl. D30—1)

FIG. 3.

FIG. 1.

FIG. 2.

FIG. 2.

FIG. 4.

The essential features of the design reside in the full line portions.

I claim:

The ornamental design for a gun holster, as shown and described.
